DUMPING TRAY FOR TROLLEY CONVEYERS

Earle V. Francis, Columbus, Ohio, assignor to The Jeffrey Manufacturing Company, Columbus, Ohio, a corporation of Ohio

Application March 9, 1931, Serial No. 521,361

17 Claims. (Cl. 198—155)

This invention relates to new and useful improvements in trolley conveyers and more particularly to attachments therefor in the nature of material carrying trays.

5 An important object of the invention is to provide an attachment of this character which will automatically cause the tray to tilt or dump to discharge material or articles therefrom at a predetermined point or points.

10 Another important object of the invention is to provide actuating means for tilting the tray in a manner to move the same bodily during tilting movements; the normal position of the tray being substantially horizontally at rest upon a support, 15 while its discharging position is at an angle of approximately 60° to the horizontal with the forward edge of the tray projected below the forward end of the support.

A further important object of the invention is 20 to provide an arrangement which will effectively support the forward end of the tray which projects beyond the forward end of its support, under the weight of any material or object placed upon the tray.

25 A still further object of the invention is to provide gravity actuated means for returning the tray to its normal position of support after the load has been discharged therefrom, and in addition cooperating means are provided to permit the 30 gradual return of the tray to normal position without shocks thereto.

A still further object of the invention is to 35 provide the load carrying arm of a trolley hanger with means for preventing swinging impulses initiated by the actuating mechanism for the tray engaging the trip mechanism for causing dumping of the tray.

Other objects and advantages of the invention 40 will become apparent during the course of the following description.

In the accompanying drawings forming a part 45 of the illustration and wherein like numerals are employed to designate like parts throughout the several views,

Figure 1 is a side elevation of a portion of a trolley conveyer embodying the present improvements and showing the tray in its normal substantially horizontal position of support;

Figure 2 is a similar view of the tray disclosed 50 in Figure 1 but shown in dumping position;

Figure 3 is a similar view showing the tray returning to normal position after the dumping operation;

Figure 4 is a transverse section taken on the 55 line 4—4 of Figure 1;

Figure 5 is a transverse vertical section through the trolley conveyer; and

Figure 6 is a fragmentary transverse section through the tray showing the one-piece construction thereof and its association with the load carrying arm of the trolley hanger. 5

Referring now more particularly to the drawings, for a detailed description of the invention, the numeral 8 designates an overhead trackway suspended by uprights 9 for the support of a 10 plurality of trolleys, one of which is shown in the drawings and which is designated in its entirety by the numeral 10. These trolley hangers may be of any desired construction but are here shown in the form illustrated in my copending 15 application Ser. No. 416,187, in which the upper end of a hanger body 11 is provided on opposite sides with rollers 12 for support upon the trackway 8 for sustaining the load carried by the 20 hanger.

Below the trackway 8, the hanger is pierced 25 with an opening paralleling the trackway for the extension therethrough of a draft device 13 consisting essentially of chain links 14 joined on vertical axes 15. At intervals in the draft element and at points where it extends through the openings in the trolley bodies, a pair of interconnected links or clevises 16 and 17 are connected to the chain links on vertical axes 18 disposed on opposite sides of the hanger body 30 30 with the clevises projecting through the opening in the hanger as shown. The inner ends of these two clevises are interconnected by a pin and slot connection as explained in the aforesaid application and the intermediate portions thereof are 35 pivotally mounted on horizontal axes 19 at opposite sides of the hanger body extending through links 20 arranged in the opening in the trolley body so that movement of one clevis produces 40 equal and corresponding angular movement of its associated clevises whereby, in traversing vertical curves in the trackway, the draft element can flex on horizontal axes without subjecting any of the parts to breaking stresses. As this 45 phase of the development is fully explained in my copending application, a further description thereof is not essential for a complete understanding of the present improvements.

Supported by means of the uprights 9 at each 50 side of the trolley body and below the same is a pair of vertically spaced guide rails 21 for a purpose which will be presently described.

Pivottally suspended from the lower end of the trolley body 11 is a load carrying arm 22 which is offset or curved rearwardly with respect to the 55

direction of travel of the hanger so that its lower end is offset with respect to the vertical center line of the hanger. The rear face of this arm adjacent its upper end is provided with a rearwardly extending bearing 23 for the support of an axle carrying limiting guide rollers 24 of a size to engage the rails 21 of each pair and to roll upon the lower rails to prevent rearward swinging of the load carrying arm as will be more fully pointed out hereinafter.

10 The lower end of the load carrying arm depends a considerable distance beneath the guide rails 21 and has secured thereto by bolts or other suitable means, a bracket 25 having a pair of forwardly extending substantially horizontal arms 26. These arms, in effect, provide the lower end of the load carrying arm with a substantially horizontally extending supporting portion constituted by the upper edges of the two arms 26. 15 These upper edges of the arms engage and support a dumping tray 27 in a substantially horizontal load carrying position as shown in Figure 1. The tray is formed from a single blank of material having its forward edge 28 rolled downwardly and its side edges 29, as shown in Figure 5, curled in the same direction. The rear portion of the tray is bent upwardly to provide a back 30, which, in the normal substantially horizontal position of the tray, is arranged vertically and 20 in close proximity to the lower end of the load carrying arm 22.

It will be observed that the forward edge of the forward portion of the tray projects a distance beyond the forward ends of the supporting arms 35 and in order to support this portion of the tray in both loaded and discharge positions of the tray, a pair of links 31 are pivotally connected as at 32 to a pair of spaced brackets 33 secured to the bottom of the forward portion of the tray to depend therefrom as shown. The lower ends of these two links are pivotally connected as at 34 to the forward ends of a pair of arms 35 fixed to shaft 36 extending transversely through the forward ends of the supporting arms 26. These 40 arms 35 are arranged against either side of the arms 26 as best seen in Figure 4, depending upon the selective location of the trip mechanisms to be presently described and collars 37 are secured to the shaft 36 on the other sides of the arms 35 to prevent the tray from shifting longitudinally of the shaft 36. Since the arms 35 are fixed to this shaft and the latter is fixed and prevented from turning in the bracket arms 26, the arms 35 are prevented from movement on the axis of the 50 shaft and consequently when the tray is in its normal substantially horizontal position, the links 31 are disposed substantially vertically to ably support the forward portions of the trays and any load sustained thereby.

60 Actuating means for dumping the tray and returning it to normal position, comprises one or more levers 38 arranged adjacent opposite sides of the tray. Each lever is substantially U-shaped, and one end 39 thereof is fulcrumed as at 40 on shaft 36 while the other end forms a trip 65 44 and terminates in a rounded end 45 constituting an anti-friction surface. The said lever is pivotally connected as at 41 to a bracket 42 secured to the bottom of the rear portion of the tray.

In order to trip the actuating levers 38 and to cause the trays to tilt to the position shown in Figure 2 to discharge a load therefrom, trips 46 are arranged in the paths of movement of the two 70 actuating levers 38. Obviously, these trips may

be arranged in various positions longitudinally with respect to the shaft 36 as indicated in dotted lines in Figure 5 to correspond with the corresponding optional positions of the actuating levers 38 along this shaft so as to provide for the selective dumping of various trays at various points or stations along the path of travel thereof.

Each trip mechanism here shown is in the form of a pair of angle plates 47 which may be supported by any suitable means and are adapted to form bearings for a shaft 48 upon which and between the plates 47, is mounted a freely rotatable roller 49 serving in the capacity of a movable trip cam. The roller is mounted rearwardly in its supporting brackets 47 so that the upper inclined edges 50 of the brackets can be folded inwardly toward each other to provide an inclined plane disposed at substantially a tangent to the trip roller 49.

20 In operation, and assuming that the tray of Figure 1 carries a load, it will be observed that the tray, while slightly inclined downwardly from its forward to its rear edge, is nevertheless in a substantially horizontal position, supported at its rear edge upon the bracket arms 26 and at its forward portion by means of the vertical disposition of the links 31. The actuating levers 38, due to the force of gravity, assume the position shown in Figure 1 with the arms 44 thereof in substantially horizontal positions and with their rounded forward ends 45 in position to engage the peripheries of the trip rollers 49 as the trolley hanger moves in a direction toward these trips.

25 As the ends 45 of the actuating levers 38 engage the trip rollers 49, the levers are swung on the fulcrumed shaft 36 causing the pivots 41 to rise and thereby tilt the tray 27 as shown in Figure 2. As the tray is tilted forwardly, it is also bodily moved forwardly, and downwardly, due to the 30 links 31 swinging on their pivots 32 and 34 simultaneously, thereby moving the links 31 to the position shown in Figure 2 at which time the load is discharged from the tray. As the free ends of the actuating lever 38 are moved over 35 the trip rollers 49, the latter turning during this engagement, and as the levers are rolled forwardly, they begin to fulcrum on the shaft in a reverse direction due to the gravitational effect of these levers until their terminals 45 engage and 40 ride down the inclined surface 50 of the trip brackets 47. During this movement, the tray is automatically and gradually returned to its normal position as the levers 38 continue to fulcrum to present their lower inclined edges and elbows 45 upon the inclined surface 50 and slide down the same until they disengage therefrom and the tray comes to rest at its rear portion on the supporting arms 26 without shocks, while the forward portion of the tray is supported by the return of the links 31 to a substantially vertical position of support. This return movement of the trays is caused by the gravitational action of the actuating levers 38 endeavoring to seek their 55 lowest level.

65 The engagement of the actuating levers 38 with the trip rollers creates a tendency for the load carrying arm 22 to swing rearwardly, but this tendency is overcome by the rollers 24 engaging 70 the guide rails 21.

It is to be understood that various changes in the construction and arrangement of parts may be resorted to without departing from the scope of the appended claims.

I claim:

1. In a trolley conveyer, a trolley hanger, a dumping tray normally supported thereby in a substantially horizontal position, and actuator means carried by the hanger and positioned beneath and engageable with the tray to cause the same to tilt at an angle to the horizontal.
2. In a trolley conveyer, a trolley hanger having a substantially horizontal supporting portion, a dumping tray normally positioned above and supported by said portion in a substantially horizontal position, and a rockable element pivoted to said supporting portion and engageable with the tray to tilt the same.
3. In a trolley conveyer, a trolley hanger having a substantially horizontal supporting portion, a dumping tray normally positioned above and supported by said portion in a substantially horizontal position, and a rockable element pivoted to said supporting portion and to the tray to cause the same to dump.
4. In a trolley conveyer, a trolley hanger having a substantially horizontal supporting portion, a dumping tray normally positioned above and supported by said portion in a substantially horizontal position, a rockable element, pivots connecting said element to said supporting portion and to the tray, and said pivots being coplanar.
5. A conveyer attachment comprising a support, a dumping tray normally supported thereby in a substantially horizontal position, a substantially U-shaped member one end of which is fulcrumed on said support and the other end of which forms a trip, said member being pivotally connected to said tray.
6. A conveyer attachment comprising a support, a dumping tray normally supported thereby in a substantially horizontal position, a substantially U-shaped member one end of which is fulcrumed on said support and the other end of which forms a trip, said member being pivotally connected to the rear portion of said tray.
7. A conveyer attachment comprising a support, a dumping tray normally supported thereby in a substantially horizontal position and adapted to be tilted to dumping position to discharge a load therefrom, and a gravity actuated trip member connected to the tray for automatically seating the same upon the support after discharge.
8. A conveyer attachment comprising a support, a dumping tray normally supported thereby in a substantially horizontal position and adapted to be tilted to dumping position to discharge a load therefrom, and a gravity actuated member fulcrumed on the support and pivotally connected to the tray for automatically seating the same upon the support after discharge.
9. A conveyer attachment comprising a support, a dumping tray normally supported thereby in a substantially horizontal position with one end projecting beyond said support, a link pivotally connected to the projecting end of said tray and to the forward end of the support and normally arranged in a position to sustain loads in the forward end of the tray, and means engageable with the tray for tilting the same upon the pivots of said link.
10. A conveyer attachment comprising a support including a pair of spaced arms, a shaft secured in the free ends of said arms, a dumping tray normally supported on said arms, a pair of links carried by the shaft and projecting for- wardly of said arms, a pair of links pivotally connected to the forward ends of the first named links and to the forward end of said tray, and an angle lever fulcrumed on said shaft and pivotally connected to the rear end of said tray.
11. In a trolley conveyer, the combination with trolley hanger mechanism, of a dumping tray normally supported thereon in a substantially horizontal position, activating means carried by said hanger mechanism and disposed below said tray, mechanism comprising a cam arm for effecting the operation of said activating means to dump the load off the tray, and means connected to said cam arm to partially counterbalance the tray and its actuating means to cause gradual movement of said tray to its horizontal position.
12. A conveyer attachment comprising a support, a dumping tray normally disposed thereabove in a substantially horizontal position with one end projecting beyond said support, auxiliary supporting means comprising a vertical link for supporting the projecting end of the tray and its load when the tray is in horizontal position, and means for tilting the tray upon said auxiliary supporting means.
13. A conveyer attachment comprising a support, a dumping tray normally supported thereby in a substantially horizontal position, a substantially U-shaped member pivotally connected to said tray, said U-shaped member being fulcrumed on said support and forming a trip and counterbalance for said tray.
14. A conveyer attachment comprising a support, a dumping tray normally supported thereby in a substantially horizontal position, a substantially U-shaped member pivotally connected to said tray, one end of said U-shaped member being fulcrumed on said support and the other end thereof forming a trip adapted to swing to both sides of the fulcrum point and at one side thereof constitute a counterbalance for said tray.
15. A conveyer attachment comprising a support, a dumping tray normally supported thereby in a substantially horizontal position, a substantially U-shaped member pivotally connected to said tray, one end of said U-shaped member being fulcrumed on said support and the other end thereof forming a trip adapted to swing beneath and to both sides of the fulcrum point and at one side thereof constitute a counterbalance for said tray.
16. A conveyer attachment comprising a support, a dumping tray normally supported thereby in a substantially horizontal position, and actuating means pivotally connected to said tray to dump the same, said actuating means being fulcrumed on said support and forming a counterbalance for said tray.
17. In a trolley conveyer, the combination with a trolley hanger, of a track therefor, a pendant rearwardly offset load carrying arm pivoted to said hanger, a substantially horizontal support fixed to the lower end of said arm, tiltable load carrying means disposed above and carried by said support, said load carrying means being constantly urged toward substantially horizontal load carrying position, tripping mechanism for said tiltable load carrying means, guiding means parallel to said track and comprising vertically spaced rails, and anti-friction means carried by said arm and located in position to engage both of said rails.
